UNITED STATES PATENT OFFICE.

GEORGE E. HAUPTMAN, OF OMAHA, NEBRASKA, ASSIGNOR TO J. DUNCAN & COMPANY, OF BOSTON, MASSACHUSETTS, A COPARTNERSHIP.

SWITCH FOR OVERHEAD CARRIERS.

No. 884,383.

Specification of Letters Patent.

Patented April 14, 1908.

Application filed January 15, 1906, Serial No. 296,176. Renewed February 29, 1908. Serial No. 418,567.

To all whom it may concern:

Be it known that I, GEORGE E. HAUPTMAN, a citizen of the United States, residing at Omaha, in the county of Douglas and State of Nebraska, have invented certain new and useful Improvements in Switches for Overhead Carriers, of which the following is a specification.

This invention relates to switches for overhead or suspension carriers.

One object is to provide a switch of the nature stated embodying such characteristics as simplicity, inexpensiveness, durability and efficiency.

15 A still further object is to provide a switch particularly designed for use in stores, factories or other houses wherein the switching of carriers from a main to a branch track or vice versa is readily accomplished.

20 A still further object resides in the provision of a switch of the nature stated embodying such characteristics that its parts may be readily assembled and so arranged with respect one element to another as to provide 25 for reliable action and operation.

With these and other objects in view, the present invention consists in the combination and arrangement of parts as will be herein-after more fully described, shown in the accompanying drawings and pointed out in the appended claims, it being understood that changes in the form, proportion, size and minor details may be made, within the scope of the claims, without departing from the 35 spirit or sacrificing any of the advantages of the invention.

In the drawings: Figure 1 is a top plan view of the invention, the dotted lines indicating the branch switching section in position. Fig. 2 is a transverse sectional view. Fig. 3 is a detail perspective view.

Referring now more particularly to the accompanying drawings, the reference character 1 designates a rail connecting web provided with a recess in its upper edge intermediate its ends to form a seat 1' for the support of the displaceable switching track sections *a* and *b*, the lower edge of the web being provided with a flange, resulting in the formation of the oppositely disposed rail seats 2 and 3. The rail sections are indicated by the reference characters 4 and 5 and are secured in their respective seats through the instrumentality of suitable bolts 6. Oppositely disposed arms 7 and 8 are formed integrally

with the connecting web upon one and the same side of the latter and directed outwardly in parallel relation therefrom.

The main displaceable track section *a* is provided with a flange 9 designed to rest upon the intermediate seat 1' of the connecting web 1 to support the switching section *a* in alinement with the main rail sections 4 and 5. Legs 10 and 11 are connected with one side of the flange 9, there being a leg at each end of the latter and each leg being provided with a foot 12 for a purpose presently explained. The heels of the feet 12 are provided with perforations 13 designed to register with the perforations 14 of the depending members 15 and 16 of the respective aforesaid arms 7 and 8 for the reception of the elongated pivot pin 16 designed to pivotally support the main switching section *a* between the arms.

The branch switching section *b* is provided with a flange 17 designed to rest upon the aforesaid intermediate seat 1' when the main switching section *a* is not disposed thereupon. At each end of the branch switching section *b* there is formed a leg, as indicated by the reference characters 18 and 19, each having its outer end reduced, as at 20, for a purpose presently explained. The leg 19 of the branch switching section *b* is provided with perforated ears 21 and 22 for the interchangeable reception of an operating rope 23. This rope 23 is designed to throw the switching sections into and out of position with respect to the rail sections 4 and 5. In most instances, the rope 23 is fixed in the perforation of the ear 21 and passes over a sheave 25 so that it may be passed the desired distance from the sheave and the main track and switches so as not to interfere with the passage of a loaded carriage over the rails and switches. The main purpose of the ear 22 is to prevent the leg 20 passing above the upper surface of the flange 9 when the main switching section is in operative position, and the operating rope 23 is fixed in the perforation of the ear 22 only when it can be done without the rope interfering with the passage of a load over the rail sections when hanging straight down from the latter. It will thus be seen that the switching sections 95

may be operated by means of a single rope and this is one of the essential features of the present invention. Obviously, the sheave 25 is not required when the operating rope is connected with the ear 22, and it will be un- 105 110

derstood that the switching sections will be thrown from one position to the other regardless of which ear may be associated with the operating rope, it simply being necessary 5 to jerk the latter quickly to throw the switching sections, the latter moving toward each other by a single operating rope. In order to permit of this movement of the switching sections toward each other is the reason 10 why the legs 18 and 19 of the branch switching section *b* are curved, as will be more clearly appreciated by a further reading of the specification.

In Fig. 3, the invention is shown positioned 15 to permit the passage of a carrier (not shown) directly over a straight line. It will be seen that in this position, the curved legs 18 and 19 of the branch switching section engage the legs 10 and 11 of the main switching section *a* just beneath the upper surface of the flange 9 of the main switching section. It will thus be understood that the main feature 20 of the reduced ends 20 of the legs 18 and 19 is to engage the legs 10 and 11 of the main switching section *a* and lock the latter in position, the effectiveness of the locking of the switching section *a* in such manner being due 25 principally to the fact that the point of contact between the legs 10 and 11 and the edge 30 of the flange 9 is immediately above the level of the horizontal center line of the pivot pin 26 of the legs 18 and 19 which would require the breaking of the switch before the main switching section could be accidentally 35 thrown out of operative position. While the reduced ends 20 of the curved legs 18 and 19 are holding the main switching section against accidental displacement, the ear 22 of the branch switching sections engages the 40 bottom of the foot 12 of the leg 11 of the main switching section and holds the former in its tilted position.

When it is desired to displace the main switching section *a* from its seat and place 45 the branch switching section *b* in its place, it is simply necessary to pull or jerk the operating cord or rope 23 whose inner end is preferably connected to the ear 21 of the branch switching section *b* when the latter will be 50 swung against its gravity over the main switching section, such movement of the branch switching section, causing the reduced ends 20 of its legs 18 and 19 to engage the feet 12 of the legs 10 and 11 of the main 55 switching section *a* and move or swing the latter upon its pivot 16 inwardly of the branch switching section *b* as the latter is being seated in its operative position. It will thus be seen that when the switching sections 60 are reversed with respect to each other they overlap, as shown quite clearly in Fig. 2. When it is desired to displace the branch switching section from its seat, a pull or jerk upon the operating cord 23, which will cause 65 the legs 18 and 19 of the branch section to en-

gage the legs 10 and 11 of the main switching section above the feet 12 thereof and force the main switching section to its seat while the branch switching section is being displaced.

From the foregoing it will be understood 70 that my improved switching mechanism embodies what may be termed a reversible frog consisting of a main section *a* and a branch section *b*, both of the latter being operated simultaneously by a mere pull or jerk upon a single operating rope arranged to be grasped by a person upon the floor beneath the track. It would appear therefore, that the present invention will be fully understood from the foregoing when considered in connection with the accompanying drawings and with the understanding that the curved track portion of the branch switching section co-operates with the curved track 27, the curved branch section having a projection *z* designed to rest 75 upon a regular rail hanger, thereby obviating the necessity of notching the rail 27. However, the projection *z* is so disposed as to allow of the use of a notched rail 27.

What is claimed is:—

1. In a switch for overhead carrier tracks, main and branch track sections, a web connecting the main track sections, arms connected to the web, main and branch switching sections pivotally mounted in said arms, one of the sections having an ear, and means connected to said ear whereby one of the switch sections may be thrown into engagement with said web while the other switch section is being taken from engagement therewith.

2. In a switch for overhead carrier tracks, main and branch track sections, a web connecting the main track sections, arms connected to the web, main and branch switching sections pivotally mounted in said arms, one of the sections having an ear, and means connected to said ear whereby one of the switch sections may be thrown into engagement with said web while the other switch section is being taken from engagement therewith, the switching sections being constructed and arranged to co-operate with each other to lock the main switching section against accidental displacement with respect 110 to the connecting web.

3. In a switch for overhead carrier tracks, main and branch switching track sections, one of the sections having ears, one of the switching track sections having interchangeable connection with the ears to operate the switching track section.

4. In a switch for overhead carrier tracks, main track sections, main and branch switching track sections, one of the switching sections having a pair of ears, and means having interchangeable engagement with the ears to throw them toward and away from each other for interchangeable co-operation with the main track sections.

5. In a switch for overhead carriers, main track sections, main and branch switching track sections, and means having connection with one of the switching sections to operate 5 both of them, the section to which the said means is connected being constructed to receive the means at two different points interchangeably.

6. In a switch for overhead carrier tracks, 10 main and branch track sections, a web connecting the main track sections and provided with a seat intermediate its ends, arms connected to said web and extending outwardly therefrom in spaced relation, a main switching section pivotally mounted in said arms for movement into and out of said seat, a branch switching section mounted in said arms for movement into and out of said seat, the main switching section having legs and 15 foot portions, the branch switching section 20

having curved legs, one of the legs of the branch switching section having a pair of ears, and means connected to one of said ears whereby one of the switching sections may be thrown into said seat while the other 25 switching section is being thrown therefrom, the curved legs of the branch switching section being constructed and arranged to hold the main switching section against accidental displacement from said seat when seated in 30 the latter, the said switching sections being moved toward each other in the operation of displacement.

In testimony whereof, I affix my signature, in the presence of two subscribing witnesses. 35

GEORGE E. HAUPTMAN.
